UNITED STATES PATENT OFFICE.

OLIVER CARMELIA, OF OTTAWA, ILLINOIS.

DESIGN FOR A TORCH-LAMP.

SPECIFICATION forming part of Design No. 18,585, dated September 4, 1888.

Application filed March 16, 1888. Serial No. 267,429. Term of patent 14 years.

To all whom it may concern:

Be it known that I, OLIVER CARMELIA, a citizen of the United States, residing at Ottawa, in the county of La Salle and State of Illinois, have invented and produced a new and original Design for Torch-Lamps, of which the following is a specification.

My invention relates to a design for campaign torch-lamps; and it consists, essentially, in providing a lamp having its oil-reservoir or body shaped externally to represent a human bust and head.

In the drawing which illustrates my design, A is the lamp, which may be supported between the forks of a bifurcated torch-stick.

B is the oil-reservoir, shaped externally in the representation of a human bust, with rounded corners and bottom, and surmounted by the head and tubular projection q.

What I claim is—

The design for a campaign torch - lamp herein shown and described, consisting of the oil-reservoir shaped externally in the representation of a human bust, with rounded corners and bottom, surmounted with a human head, as set forth.

OLIVER CARMELIA.
